Primary Examiner — T. Chase Nelson*Assistant Examiner* — Jonathan J. Han(74) Attorney, Agent, or Firm — Amster, Rothstein & Ebenstein LLP(57) CLAIM

The ornamental design for a belt buckle with bottle opener, as shown and described.

DESCRIPTION

FIG. 1 is a bottom perspective view of the belt buckle with bottle opener showing the present design.

FIG. 2 is a bottom plan view thereof.

FIG. 3 is a top plan view thereof.

FIG. 4 is a right side view thereof.

FIG. 5 is a left side view thereof.

FIG. 6 is a front view thereof; and,

FIG. 7 is a rear view thereof.

The portions of the design shown in broken lines being for the purpose of illustrating environment only and form no part of the claimed design.

1 Claim, 5 Drawing Sheets(56)
